J. PETERSON

DISPENSING POUCH OR PACKAGE

Filed Dec. 4, 1922

UNITED STATES PATENT OFFICE.

JONATHAN PETERSON, OF BROOKLYN, NEW YORK, ASSIGNOR TO COMBINATION MACHINE COMPANY, OF NEW YORK, N. Y., A CORPORATION OF DELAWARE.

DISPENSING POUCH OR PACKAGE.

Application filed December 4, 1922. Serial No. 604,793.

To all whom it may concern:

Be it known that I, JONATHAN PETERSON, a citizen of the United States, and resident of Brooklyn, in the county of Kings and State of New York, have invented certain new and useful Improvements in Dispensing Pouches or Packages, of which the following is a specification.

This invention relates to a container especially adapted for the packaging of small quantities of tobacco or similar commodities, and especially to a dispensing closure for such containers, and also to other features of tobacco or similar packages adapted for carrying in a garment pocket.

The invention comprises improvements in the form of closure shown in my previous application Serial No. 465,898 filed April 30, 1921, and additional features, as explained hereafter.

An important object of the invention is to provide improved means for fastening the mouth end of a tobacco pouch of paper or similar fibrous sheet material so as to provide a suitable closure for the pouch, and at the same time provide more effectively for the opening of the discharge aperture in the mouth end of the pouch when the pouch is properly manipulated to discharge the contents.

Another object is to provide a package including an inserted piece of stiffening material such as a card which aids in maintaining the desired form of the package prior to its opening by the consumer, in cooperation with a dispensing closure arranged to permit the card to be easily withdrawn when the package is opened.

The characteristics and advantages of the invention are further sufficiently explained in connection with the following detail description of the accompanying drawings, which show one exemplifying embodiment of the invention. After considering this embodiment, it will be evident that variations in structure can be made, and I do not limit myself to details, except as claimed.

In the drawings:

Fig. 1 is a perspective view of a complete closed package.

Fig. 2 is a section of the upper portion of the package at 2—2, Fig. 1.

Fig. 3 is a perspective view of the upper end of the container with the neck or mouth portion unrolled.

Fig. 4 is an enlarged detail section at 4—4, Fig. 3.

Fig. 5 is a section at 5—5, Fig. 3.

Fig. 6 is a perspective view showing the manipulation of the package for discharging the contents.

Fig. 7 is a perspective view of the upper end of the package showing a slightly modified dispensing opening and sufficiently illustrating a multi-ply pouch wall construction.

The complete package as illustrated in Figs. 1 to 6 inclusive comprises a bag or pouch 10 of substantially rectangular and oblong form filled with tobacco 11 or other granular or comminuted material, and having an upper neck portion 12 shown extended in Fig. 3, which in the completed package is folded or rolled substantially flat on the upper end of the package as shown in Figs. 1 and 2 and secured in any suitable way, for instance by a revenue stamp 13, Fig. 1. Desirably, although not necessarily in all cases, a piece of fairly strong and stiff material such as a card 14 (Figs. 2 and 5), is placed on top of the contents just below the rolled or folded neck 12.

The pouch 10 is made of any suitable material, usually flexible fibrous sheet material and paper of suitable grade and thickness is usually the most desirable material for the purpose. The pouch is made up in the form of a bag having a closed substantially flat bottom 15, broad sides 16 and 17, narrow ends 18, and a narrow top 19, all these faces of the package being most conveniently of substantially rectangular form. The upper or neck portion of the pouch is creased to provide inwardly extending or tuck folds 20 (Figs. 3 and 5).

The upper portions of the pouch sides 16 and 17 lie close together when the neck is extended, as best shown in Fig. 3, and after the pouch is filled and the card 14 inserted, when such a card is used, fastening devices such as the clips 21 are applied to the upper marginal portions of the neck near each end thereof to hold the sides firmly together for some distance from each end of the neck portion toward the center. These fastening devices may vary greatly, but in a preferred embodiment of the invention they consist of sheet metal clips having sides 22 and 23 connected by a bendable portion 24. The one side member 22 is provided with inwardly

bent prongs 25, and the other side portion is provided with prong sockets 26. Normally the clips are produced in more or less open form with the prongs straight and projecting inward, and they are so applied to the bag neck in the positions shown in Fig. 3, and then pressed by suitable tools or merely by pressure of the fingers of the operator, whereupon the side portions of the 10 clip are bent into parallel position as shown in Fig. 4, and at the same time the prongs are forced through the bag neck material and are bent upward in the prong sockets 26. The clips are thus firmly locked in position and the bag mouth or neck is firmly secured with its side portions in flat contact for some distance inward from the outer ends, as shown in Fig. 3. This fastening arrangement leaves an intermediate portion 15 of the neck side members free, forming a dispensing opening 30 which may in some cases consist of the normally straight edges of the bag side material or more desirably, as shown in Fig. 3, the edges of the bag sides are cut inward somewhat, usually with a shallow curvature. Normally the edges remain in flat contact between the fastening devices 21. The bag neck is then folded or rolled compactly on top of the package, as 20 shown in Figs. 1 and 2. When the card 14 has been previously inserted, as above described, it serves to maintain the upper end of the package in the desired rectangular form, for convenience in labelling or other 25 manipulation of the packages, and packing the packages in cartons or boxes.

When it is desired to utilize the contents of the package, the upper or neck portion of the pouch is unrolled after breaking the 40 revenue stamp or other seal or fastening which may be used to hold it in rolled or folded position, and pressure is applied substantially at or near the ends of the fastening devices 21, whereupon the dispensing 45 opening 30 is spread or gaped open as shown in Fig. 6 and the desired amount of the contents may be poured out into a pipe bowl or cigarette paper. The stiff fastening devices 21 assist materially in localizing the pressure applied in opening the package, so that 50 the bending effect is applied to the opening 30, and the marginal portions of the neck adjacent to the opening are caused to bulge divergently to produce a suitable discharge 55 opening of substantially the shape shown in Fig. 6.

When an internal supporting member such as the card 14 is used, it has to be withdrawn as soon as the package is first opened, and 60 this withdrawal is easily accomplished by applying pressure to the end walls 18 of the package opposite the ends of the card sufficient to cause the card to buckle or break upwardly near its center. This buckled or 65 sharply bent portion of the card can then

easily be grasped through the dispensing opening 30, and the card bent still more until its end portions are substantially parallel, and the card can then be easily removed through the opening and thrown 70 away, leaving the contents free to be discharged as required in the manner previously described.

The above identified application describes the material which may be used for making 75 the pouch. Multi-ply or moisture-proofed material such as described in that application may be used in the pouch as shown in Figs. 1 to 6, but for the sake of simplicity 80 in the drawing, the pouch material is shown as consisting of a single thickness or sheet of material. Fig. 7 sufficiently illustrates a multi-ply construction in which the outer layer of material may be as described in connection with the preceding figures, and another or inner layer of sheet material 40 may be located within the outer material. When 85 this inner material is extended to the upper end of the pouch, the pouch walls adjacent to the dispensing opening are of multi-ply 90 construction as clearly shown in Fig. 7. In this embodiment of the invention, the closure 95 clips 21^a are relatively shorter than in the previous example, leaving room for a somewhat longer dispensing opening 30^a, and the 100 shape of this opening is also somewhat modified, the modification consisting in cutting the material down substantially parallel to the inward ends of the fastening clips and then cutting the material straight across to 105 provide a substantially straight-edged dispensing opening substantially in line with the lower edges of the clips 21^a.

In addition to stiffening the pouch end or mouth adjacent to the dispensing opening, and thus facilitating the spreading of the opening for the discharge of the package 110 contents, the closure clips 21 of sheet metal or other substantially stiff material are more easily and economically manipulated and applied to the package in some cases than the sealing strip of relatively flexible sheet material employed in the above-identified application.

I claim:

1. A dispensing container comprising a pouch of flexible sheet material having a neck with separable outward or mouth margins normally in flatwise contact, and separate fastening clips of relatively stiff sheet material securing the opposite neck margins together at the sides thereof, closing end portions of the mouth and leaving a dispensing opening between the clips which may be sprung divergently by endwise pressure.

2. A dispensing container comprising a pouch of flexible sheet material having a neck with outward or mouth margins normally in separable flatwise contact, and

sheet metal fastening clips securing the opposite neck margins together at the sides thereof, closing end portions of the mouth and leaving a dispensing opening between the clips which may be sprung divergently by pressure applied in the endwise direction of the clips.

3. A dispensing container comprising a pouch of flexible sheet material having side and end walls terminating in a neck consisting of the side walls and the inwardly folded end walls, the end margins of the side walls being secured in contact by fasteners of relatively stiff sheet material located near the ends of said margins and closing end portions of the container mouth, the side wall edges intermediate the fasteners constituting a distensible dispensing opening.

20 4. A dispensing container comprising a pouch of flexible sheet material having side and end walls to enclose the container contents, the walls terminating in a foldable neck consisting of the side walls and the inwardly folded end walls, the end margins of the side walls being secured in contact by sheet-metal fasteners having connected side portions and prongs passing through the pouch walls, said fasteners being located 25 near the ends of said margins, the side wall edges intermediate the fasteners being shaped to form a dispensing opening.

5. A tobacco package comprising a pouch of flexible sheet material in substantially 30 rectangular and flat form and rectangular horizontal cross-section and closely fitting the contents of granulated or comminuted

tobacco, the pouch having an upper neck portion terminating in a dispensing closure which includes stiff fastening members securing edges of the neck mouth in flatwise contact with an intermediate dispensing opening between said fastening members, and a stiffening card of bendable material on top of the contents within the pouch, 40 the pouch neck being folded compactly down upon the card, the dispensing opening being distendable to permit easy removal of the card by bending the latter after the pouch neck is unfolded.

6. A tobacco package comprising a pouch of flexible sheet material in substantially rectangular and flat form and elongated, rectangular, horizontal cross section and closely fitting the contents of granulated 45 or comminuted tobacco, the pouch having an upper neck portion terminating in a dispensing closure which includes sheet-metal fastening members securing edges of the neck mouth in flatwise contact and closing end portions of said mouth with an intermediate dispensing opening between said fastening members, and a stiffening card of breakable material on top of the contents within the pouch, the pouch neck 50 being folded compactly down upon the card, the dispensing opening being distendable to permit easy removal of the card by bending the latter after the pouch neck is unfolded.

Signed at New York city in the county of New York and State of New York, this 29th day of November A. D. 1922.

JONATHAN PETERSON.
